FOLDING CHAIR

Clarence F. Benjamin, Devon, Conn.

Application February 25, 1942, Serial No. 432,221

3 Claims. (Cl. 155—117)

This invention relates to folding chairs, and has for an object to provide an improved and simplified construction which can be instantly opened or folded, and when folded the members lie side by side so that in this condition it requires a minimum of space.

It is also an object to provide a construction having a flexible back and seat in which the chair can be adjusted to various positions and inclinations of the back, and in which the adjustments also adjust the length of the seat and back, so that all elements of the chair are adjusted for different positions and the seat and the back are elongated for the reclining position and shortened for the upright position.

With the foregoing and other objects in view I have devised the construction illustrated in the accompanying drawings forming a part of this specification. It is, however, to be understood the invention is not limited to the specific details and arrangement shown but may employ various changes and modifications within the scope of the invention.

In these drawings:

Fig. 1 is a side elevation of the chair in the upright position for use;

Fig. 2 is a similar view of the chair in its extreme reclining position;

Fig. 3 is a side elevation of the chair in folded position;

Fig. 4 is a detail section of one form of locking means;

Fig. 5 is a side elevation thereof;

Fig. 6 is a side elevation of a sunshade which may be used;

Fig. 7 is a front elevation of the chair in folded condition;

Fig. 8 is a vertical section of the chair in the condition of Fig. 1 but taken on a plane corresponding to the line 8—8 of Fig. 7;

Fig. 9 is a side elevation of the front portion of the chair showing a modified arrangement of adjusting means;

Fig. 10 is a side elevation of the adjusting means with the leg and brace removed;

Fig. 11 is a section substantially on the line 11—11 of Fig. 10;

Fig. 12 is a similar view to Fig. 9 showing another modification;

Fig. 13 is an elevation of the adjusting means with the leg removed;

Fig. 14 is a section substantially on the line 14—14 of Fig. 13;

Fig. 15 is a side view showing still another modification, and

Fig. 16 is a section substantially on the line 16—16 of Fig. 15.

The improved chair construction comprises laterally spaced side frames connected by transverse bars. Each side frame comprises a back member 1 and front and rear leg members 2 and 3 and a link member 4. In a set-up condition for use the leg members 2 and 3 are inclined downwardly in opposite directions. They are pivotally connected at their upper ends at 5. Intermediate its length the rear leg member 3 is pivoted to the back member at 6 and the link 4 is pivotally connected to the lower end of the back member at 7 and to the intermediate portion of the front leg member 2 at 8. The connections 7 and 8 may be cross rungs or bars connecting the side frames. To give increased strength and stiffness, similar bars 9 may connect the lower ends of the front and rear leg members and a similar bar 10 connects the upper ends of the back members. It is preferred that the pivotal connections 6 and 8 be substantially at the middle of the leg members 3 and 2 so that the lengths of the leg members on opposite sides of these pivots are substantially equal. It is also preferred that the length of the back members between the pivots 6 and 7 and the length of the link 4 be substantially the same and equal to one-half the lengths of the leg members, or that is, that the distances between the pivots 5 and 6, 5 and 8, 6 and 7, and 7 and 8 be substantially equal, although it is not necessary that these dimensions be used. If these dimensions are employed the lower ends of the back members 1 and the link 4 can be arranged to rest on the ground or floor 11 with the lower ends of the leg members in all positions to provide additional support for the chair, which is particularly desirable when the chair is in the reclining position as indicated in Fig. 2, as due to the assumed angles of the various members this is the position of greatest strain on the leg and back members. It will be seen the upper portions of the leg members 2 and 3, the lower portion of member 1 and the link 4 form a diamond construction which is adjustable within large limits, so the chair can be adjusted with the lower ends of the leg members close together with the back nearly vertical and a small seat, or with the lower ends of the legs spread backwardly and forwardly the back may be brought nearly to the horizontal so the user can lie nearly straight. The back member 1 and the front leg member 2 are in the same plane while the link 4 is on the inner sides of these members and the rear leg member 3 is on the outer side thereof. This therefore permits the

chair to be folded with the members 1 and 2 lying side by side as shown in Fig. 3, permitting the chair to be folded to a position requiring the minimum of space.

The seat and back member is formed by a single flexible member 12 which may be of some fabric such for example as canvas, connected at its upper end to the bar 10 and at its other end to a roller 13 extending between and supported by the front leg members 2 and so mounted as to be rotatable to wind or unwind this member thereon. This roller may form the transverse rung or bar connecting the front leg members. Beneath this member 12 is a flexible seat support 14 which may also be of similar fabric as canvas and it is connected at its rear end to a transverse bar 15 extending between and supported by the rear leg members 3 and also connected at its forward end to the roller 13. This being beneath the seat portion of the member 12 forms an additional support for this member to retain it in the proper position. It also acts as a limiting and adjusting means for the chair. That is, as the roller 13 is rotated to wind the members 12 and 14 thereon the front and rear leg members 2 and 3 are drawn together or toward each other to adjust the position of the chair, making it more upright and reducing the length of the seat portion. By permitting rotation of the roller in the opposite direction and unwinding these flexible members, the lower ends of the leg members are permitted to spread farther and farther apart to permit the chair to move to the reclining position, the limit of this movement being shown in Fig. 2. This of course may be determined by the length of the member 14, but it is preferred to also provide limit stops 16 on the inner sides of the front leg members 2 to engage the tops of the links 4 in this position, to not only limit the movement but also provide additional support in this extreme position. The upper portions 2a and 3a of the leg members form arm rests, and it will be seen that as the chair is adjusted between the upright and reclining positions these rests are also automatically adjusted for different heights, being lower in the reclining position.

Means is provided to retain or lock the roller 13 in different adjusted positions to maintain the chair in the different adjusted positions. Different forms of locking or retaining means may be used but that shown in Figs. 1 to 7 comprises a ratchet 17 secured to the roller and having any desired number of notches, cooperating with a pivoted pawl 18, the pivot of the pawl being shown at 19. A spring 20 engages the pawl and is arranged to hold the pawl in either the holding or released position. The spring extends around two supporting screws 21 and has its free end 22 engaging an extension 23 on the pawl so that the pressure of the spring tends to hold the lug 24 of the pawl in the notches in the ratchet. When the pawl is swung to the dotted position in Fig. 5 the free end of the spring engages the top wall of the pawl and retains it in this released position. It can be swung down to the holding position by merely swinging its free end downwardly. The other free end of the spring 25 is extended under the portion 22 as shown and provides an additional support and additional pressure of the spring on the pawl. For adjusting the roller the ratchet 17 may have an extension or hub 26 forming a hand grip for rotating the roller. It will be evident that with this arrangement fine adjustments may be made depending on how

much the members 12 and 14 are wound onto the roller, the different notches on the ratchet permitting small adjustments so that adjustments may be readily made to suit the user and place the chair in the condition most comfortable for him. To adjust the chair from the upright position of Fig. 1 to the reclining position of Fig. 2, all that is necessary is to release the roller and the weight of the user or pressure on the chair will move it to this position, or the roller may be rotated by hand. If it is desired to fold the chair for carrying or storage this operation may be readily performed by pulling forwardly on the upper part of the back and pressing rearwardly on the front of the roller, bringing the chair to the position of Fig. 3. It can be as readily opened up to the usable position. When the chair is folded the roller 13 may be rotated to wind the member 14 thereon and bring it taut as shown in Fig. 3. In this position member 14 holds or locks the chair in the collapsed or folded condition which greatly facilitates handling. To again set up the chair for use the roller must be released by releasing the pawl and ratchet to permit unwinding of the member 14.

This construction permits the use of an improved sunshade 21. This may comprise two side members 28 each made up of two rigid members 29 of wood or similar material connected by screws or rivets 30 and a clamping bolt 31. They are notched at the rear end to grip the bar 10 but the width of the opening between the jaws 32 is preferably less than the diameter of the bar 10 and the width of the notch to the rear of the entrance of the notch so as to more firmly grip the rod 10 and not slide off it unless the jaws are separated sufficiently to permit the rod 10 to pass between the members 32. Extending between the side members 28 is a shade member 33, preferably a flexible member such as canvas, and it can be mounted by fastening between the two members 29 as by tacks or other means. This leaves the two side members 28 free to be adjusted independently about the member 10 so that if desired the shade can be inclined to different angles as indicated in dotted lines Fig. 7, should the sun be coming from the side or for any other reason. The members 28 can be clamped in any desired position on the member 10 by merely clamping the thumb screws 34.

Figs. 9 to 16 show different modified arrangements for holding the adjusting roller 13 in different positions to adjust the length of the members 12 and 14. In the arrangement of Figs. 9 to 11 the extension 35 of the roller is flattened as shown at 36 and the ends of the links 4 are extended somewhat as shown at 37 and are provided with a keyhole shaped opening the round portion 38 of which is of a size to permit turning of the member 36 therein, while leading downwardly from this opening is a flat narrow portion or notch 39 to receive the portion 36. By shifting the roller upwardly and forwardly to carry the flattened portion 36 into the circular portion 38 of the opening the roller may be rotated to wind or unwind members 12 and 14 and then by sliding the flattened portion 36 into the notch 39 the roller is locked in this adjusted position. By having the notch 39 extend downwardly or rearwardly from the circular portion 38 weight of the user on the seat of the chair tends to hold the flat portion in the notch so that there is no danger of the roller being accidentally released in use to permit collapse of the chair. With this construction the members can

be made of wood, saving metal. Although the roller is mounted in extensions of the links 4 these links are connected to the leg members at 8 and therefore the effect is the same as if the roller were mounted in the leg member. In fact it is so mounted in the other figures of the drawings.

A similar arrangement is shown in Figs. 12 and 14, but here instead of having the keyhole shaped opening in an extension of the link 4 it is formed in the leg member 2 the round portion of this opening permitting rotation of the flat 35 as shown at 40 and the notch leading therefrom as shown at 41 extending downwardly and backwardly from the circular portion so that weight on the chair seat will automatically retain the flat portion 35 in the notch. In this arrangement the extension 35 of the roller can turn in the link 4 and therefore this extension forms the pivotal connection between the link and the leg member 2.

In Figs. 15 and 16 a ratchet 42 is secured to the extension 43 of the roller with a hand grip 44 for turning it. A flat pawl 45 is pivoted in a slot 46 in the leg member 2 with its free end extending laterally to seat in the notches in the ratchet 42. A flat spring 47 may engage either of the flat edges 48 or 49 of the pawl arranged at an angle to each other to either tend to hold the pawl in engagement with the ratchet as shown in full lines, or retain it released as shown in dotted lines, as in the case of Figs. 1 to 7. It is preferred to use one of these pawls and ratchets on each end of the roller. It is also preferred to use the holding means of Figs. 9 to 14 at each end of the roller.

It will be seen from the foregoing description that this chair may be opened or folded instantly, and that it may be used in any one of many positions from the upright to the reclining positions because of the fine adjustments securable with the roller and locking means shown. This roller adjusts the seat, back and arm rests all together and all at the same time, and small partial turns of the roller permit of fine adjustments and shapes the seat, back and arm rests to conform to the user and bring them to the most comfortable position. The lower ends of the back members act as braces to the rear legs and the links 4 act as braces to the front legs, giving greater support and strength to the chair and giving greater or extra support where they are of such length as to rest on the floor or ground. The roller takes up all the stretching and sagging of the fabric of the seat and back members and the seat support, thus overcoming the sagging of fabric and the resulting change and uncomforatableness so common in folding chairs. However, when the chair is in the folded position the roller may be rotated to draw the seat support 14 taut, thus holding and locking the chair in the folded position, making it much easier to handle or carry and facilitating transportation and storage.

Having thus set forth the nature of my invention, what I claim is:

1. A folding chair comprising laterally spaced side frames connected by transverse bars, said side frames including front and rear leg members pivoted together at their upper ends, a back member pivoted intermediate its length to the intermediate portion of the rear leg member, a

link pivoted to the lower end of the back member and the intermediate portion of the front leg member, a rotatable roller mounted in and extending transversely between the front leg members, a flexible back and seat connected to the upper part of the back members and said roller, a rear cross bar mounted in and extending between the rear leg members, a flexible seat support under said seat connected to the roller and said rear cross bar and serving to limit the amount of separation of the front and rear leg members, said roller being rotatable to wind and unwind said back and seat member and the seat support thereon to vary the limit of separation of the front and rear leg members, and means for holding the roller against turning.

2. A folding chair comprising laterally spaced side frames connected by transverse bars, said side frames including front and rear leg members pivoted together at their upper ends, a back member pivoted intermediate its length to approximately the middle of the rear leg member, a link pivoted to the lower end of the back member and approximately the middle of the front leg member, the lengths of said link and the lower portion of the back member below its pivot to the rear leg member being approximately the same as the lower halves of the leg members, a rotatable roller extending transversely between the front leg members, a transverse bar between the upper parts of the back members, a flexible back and seat connected to said bar and roller, a transverse bar between the rear leg members below said flexible back and seat, and a flexible seat support connected to said latter bar and said roller under the flexible back and seat and serving to limit the amount of separation of the front and rear leg members, said roller adapted to wind said flexible members thereon to adjust their lengths to vary the limit of separation of the front and rear leg members and means for holding the roller against turning.

3. A folding chair comprising laterally spaced side frames connected by transverse bars, each side frame comprising oppositely and downwardly inclined leg members pivotally connected at their upper ends, a back member pivoted at a point above its lower end to an intermediate portion of the rear leg member and a link pivotally connected to the lower end of the back member and an intermediate portion of the front leg member, a rotatable roller extending transversely between the front leg members, a transverse bar between the upper parts of the back members, a flexible back and seat connected to said bar and roller, a transverse bar between the rear leg members below said flexible back and seat, a flexible seat support connected to said latter bar and said roller under the flexible back and seat, said roller adapted to wind said flexible members thereon to adjust their lengths, the ends of the roller being flattened, a member of each frame having a keyhole shaped opening in which a flattened end of the roller extends, the wider portion of which opening is of sufficient diameter to permit turning of said flattened portion therein to adjust the length of the flexible members and the narrower portion of the opening being a notch extending rearwardly from the wider portion to receive said flattened end and hold it against turning.

CLARENCE F. BENJAMIN.
